2 Claims. (Cl. 204—82)

1

This invention relates to a process for the manufacture of acid solutions of ammonium persulphate by electrolysis using electrolytic cells having a stationary catholyte. Such solutions can be hydrolysed and distilled to yield hydrogen peroxide or treated to give ammonium persulphate crystals.

In the electrolytic conversion of acid solutions of ammonium sulphate to ammonium persulphate it is usual to surround the cathode with a diaphragm to prevent the ammonium persulphate formed being decomposed and to obtain the maximum current efficiency. Such diaphragms are made of porous ceramic material, of asbestos, of microporous ebonite, or other suitable material. It is possible in this electrolysis to use cells having separate chambers for anolyte and catholyte both of which flow continuously through the cell. With such an arrangement the catholyte is always acid in reaction but this involves controlling and handling two separate flows of electrolyte through the cell with consequent multiplicity of plant and controls. It is therefore advantageous to employ a single chamber cell in which the catholyte is stationary while only the anolyte is discharged continuously.

In the type of process using a stationary catholyte a porous ceramic diaphragm is used and, as stated above, the anolyte flows continuously through the cell, eventually being discharged as an acid solution of ammonium persulphate, while the catholyte remains in the diaphragm chamber and is therefore stationary. The diaphragms heretofore used have been very loosely fitting so that there is always a considerable volume of stationary catholyte in the diaphragm. As the electrolysis progresses the concentration of ammonium ions in this stationary catholyte increases and this increase in ammonium ions eventually results in an alkaline condition in the catholyte. This alkaline catholyte has an increased electrical resistance thus increasing the potential difference across the cell. Also the alkaline condition of the catholyte results in the precipitation of the oxides of the metallic impurities present in the solution. This precipitation occurs in the body of the diaphragm at the alkali-acid interface and results in the blocking up of the pores of the diaphragm with a consequent increase in the resistance of the diaphragm. A further disadvantage resulting from this alkaline catholyte is that this alkaline solution attacks the ceramic diaphragm material causing it to break down so that the pores become blocked which again leads to an increase in

2

resistance. This problem of attack cannot be solved by altering the composition of the ceramic material as it has not yet been found possible to manufacture ceramic diaphragm material which is simultaneously resistant to both acid and alkaline solutions. This increased resistance of catholyte and diaphragm causes an increase in the potential difference across the cell leading to an increased consumption of electrical energy per unit of ammonium persulphate produced, as well as to an increase in the amount of cooling required to maintain the cell at its efficient working temperature. A further consequence is the loss of ammonia from the system owing to its evolution from the alkaline catholyte.

It has now been found according to this invention that the above disadvantages of using ceramic diaphragms with a stationary catholyte can be obviated if the liquid within the diaphragm is always maintained acid in reaction and if a closely spaced porous ceramic diaphragm is used.

Accordingly, the present invention provides a process for the manufacture of acid solutions of ammonium persulphate by the electrolysis of acid solutions of ammonium sulphate using an electrolytic cell having a stationary catholyte wherein the catholyte is maintained acid in reaction throughout the electrolysis and wherein the cathode is surrounded by a closely spaced porous ceramic diaphragm.

Preferably platinum anodes and graphite cathodes are employed. A cell suitable for carrying out the process of the present invention is shown in the accompanying drawings in which Fig. 1 shows a longitudinal sectional view of the cell and Fig. 2 shows a plan view of part of the cell.

Referring to the drawings, the cell 1 contains a plurality of cathodes 2 screwed into a bar 3 of the cell, each cathode being surrounded by a closely fitting porous ceramic diaphragm 4. The anodes 5 are disposed in the anolyte 6 the level of which is indicated at 7. The anolyte solution is led into the cell 1 through an inlet pipe 8 and discharges through an overflow pipe 9.

It has been found that the best results are obtained when the distance between the cathode and inner surface of the diaphragm does not exceed 3 mm. at any point.

In order to achieve the desired conditions of continuous acidity in the diaphragm coupled with a low potential difference across the cell together with maximum energy efficiency it was found that the leakage of electrolyte through the porous diaphragm material had to be within

certain limits in order that there was sufficient flow of acid electrolyte into the diaphragm to maintain the catholyte acid in reaction. The factors which affect this leakage are the permeability of the ceramic diaphragm material and the depth of electrolyte outside the diaphragm. The depth of liquid outside the diaphragm when it is placed in the cell is referred to herein as the "working level of the diaphragm." An increase in the permeability of the ceramic material or an increase in the working level of the diaphragm with fixed permeability both lead to an increased leakage of electrolyte through the diaphragm, and these two factors must be varied to obtain the desired leakage. We measure the permeability of the diaphragm as follows: The leakage is expressed as the amount of water which can flow to air through unit area of the diaphragm per minute. It was found that the limits of leakage for a suitable porous ceramic diaphragm lay between 10 and 40 mls. of water per sq. dm. per minute when it is filled to its working level with water.

In order to achieve the desired electrolysis conditions it was also found preferable to limit the current density to a figure between 3 and 12 amps per sq. dm. at the cathode.

A preferred embodiment of this invention for the manufacture of acid solutions of ammonium persulphate comprises electrolyzing an acid solution of ammonium sulphate between a platinum anode and a cathode which is enclosed in a porous ceramic diaphragm of such dimensions that the distance between the cathode and the inner surface of the diaphragm does not exceed 3 mm. at any point, using a current density of between 3 and 12 amps. per sq. dm., the ceramic diaphragm being constructed of such porous material that the leakage of water to air per sq. dm. of the diaphragm is between 10 and 40 mls. per minute when filled to the working level (measured as hereinbefore defined).

Under these conditions the stationary catholyte remains continuously acid and ammonium persulphate solutions are produced with an improved energy efficiency, no ammonia is lost from the system and the condition and life of the diaphragm are greatly improved. Also such an arrangement of closely spaced ceramic diaphragms is very economical in space for the general electrode assembly which is capable of easy multiplication for the construction of large units.

As indicated above the acid solution of ammonium persulphate obtained may be hydrolysed and distilled to give hydrogen peroxide or it may be converted into ammonium persulphate crystals in ways well known to those skilled in the art.

As mentioned above, a number of advantages result from the employment of a catholyte which is continuously acid in reaction. Thus, the ohmic resistance of catholyte and diaphragm, and hence the potential difference across the cell, is reduced. A high current efficiency is obtained together with a high yield per unit of electrical energy. There is no alkali build up in the catholyte and hence no blocking up of the pores of the diaphragm with consequent disintegration.

The following example illustrates how the process of the invention may be carried into effect:

An acid solution of ammonium sulphate having the following composition: 200 gms./litre $(\text{NH}_4)_2\text{SO}_4$ and 300 gms./litre H_2SO_4 , was electrolysed in a cell having platinum anodes and a

carbon cathode surrounded by a porous ceramic diaphragm, 36 mm. outer diameter, 1.5 mm. wall thickness, having a leakage to air of 80 cc./min. of water when filled with water to its working level of 50 cms. and the distance between the ceramic diaphragm and the carbon cathode was 2 mm. The current was 30 amps on the cathode, i. e., about 6 amps per sq. dm. Throughout the electrolysis it was found that the catholyte continuously showed an acid reaction. The potential difference across the cell was 4.9 volts. The energy efficiency was 0.85 kwh/lb. of ammonium persulphate when the concentration of the ammonium persulphate solution produced was 260 gms./litre. After the cell had been running continuously for 12 months the diaphragm was strong and in good condition and the original leakage was unimpaired showing that there had been no blockage of the pores.

We claim:

1. In the manufacture of solutions of ammonium persulphate by electrolysis carried on in a diaphragm cell wherein a substantially stationary body of catholyte is maintained on the cathode side of said diaphragm with the diaphragm spaced from said cathode a substantial distance but not exceeding 3 mm., the improvement which comprises subjecting an acid solution of ammonium sulphate as anolyte to electrolysis in said cell while causing a leakage of said anolyte through said diaphragm to the catholyte side thereof sufficient to maintain the catholyte acid in reaction during the course of the electrolysis, and maintaining a current density of between 3 and 12 amps. per sq. dm. of the immersed surface of said cathode.

2. In the manufacture of solutions of ammonium persulphate by electrolysis carried on in a porous ceramic diaphragm cell wherein a substantially stationary body of catholyte is maintained on the cathode side of said diaphragm and the cathode is spaced from the diaphragm a substantial distance but not exceeding 3 mm., the improvement which comprises subjecting an acid solution of ammonium sulphate as anolyte to electrolysis in said cell at a current density on the cathode of between 3 and 12 amps. per sq. dm. while causing a leakage of said anolyte through said diaphragm to the catholyte side thereof during the course of the electrolysis equivalent to a leakage of water to air of from 10 to 40 mls. per sq. dm. per minute when a diaphragm of like porosity is filled to the working level with water.
